UNITED STATES PATENT OFFICE.

JOHN GEORGE AULSEBROOK KITCHEN, OF LANCASTER, ENGLAND, ASSIGNOR OF ONE-HALF TO GORDON HENRY FRASER, OF LIVERPOOL, ENGLAND, AND JAMES RYDER O'HANLON, OF WESTWOLD, ENGLAND.

BOAT STEERING AND REVERSING GEAR.

1,315,514.

Specification of Letters Patent.

Patented Sept. 9, 1919.

Application filed May 13, 1919. Serial No. 296,834.

To all whom it may concern:

Be it known that I, JOHN GEORGE AULSEBROOK KITCHEN, of 7 Rose Bank, Scotforth, Lancaster, in the county of Lancaster, England, a subject of the King of Great Britain and Ireland, have invented certain new and useful Improvements in Boat Steering and Reversing Gears, of which the following is a specification.

10 This invention relates to boat steering and reversing gear of the type such as described in prior Patent No. 1,186,210, in which two rudders are so arranged that they deflect or reverse the stream of water driven astern by the propeller in order to effect steering and reversal of the boat without varying the speed or the direction of rotation of the propellers.

20 The object of the present invention is to provide a compact and simple form of gear having a minimum of joints or connections in which lost motion can occur and capable of being operated by hand or by power to suit requirements.

25 The invention comprises the combination with a sector or its equivalent upon each rudder stock, of chains or like flexible connections attached to such sector at the opposite ends of its circular face and in opposite directions to an operating pulley or its equivalent, the two flexible connections of each sector passing over separate guide or jockey pulleys carried by a slide, with means for traversing the slides simultaneously in opposite directions, for the purpose described.

Referring to the accompanying explanatory drawings:—

Figure 1 is a plan view, Fig. 2 a sectional elevation, Fig. 3 a front elevation, Fig. 4 an end view looking from left to right of Figs. 1 and 3, with certain parts omitted, and Fig. 5 an end view looking from right to left of Figs. 1 and 3 with certain parts omitted, 45 of a rudder control gear constructed in one convenient form in accordance with my invention.

Fig. 6 is a diagram to illustrate the action of the gear.

50 Fig. 7 is a diagrammatic perspective view

of rudders arranged in one convenient form for control by the gear illustrated in Figs. 1 to 5.

Figs. 8 and 9 illustrate in plan and front elevation respectively a modified application 55 of the invention.

Figs. 10, 11 and 12 illustrate in diagram form a further modified application of the invention.

The same reference letters in the different 60 views indicate the same or similar parts.

The rudders *a*, *b* are mounted on a concentric sleeve and spindle *c*, *d* forming rudder stocks, and to the upper end of the spindle is fixed a sector *e*, while a similar sector *f* is mounted on the sleeve *c*. Each sector has two grooves *g*, *h* in its circular face which serve to receive the guide chains, wire ropes or like flexible connections *i* (shown diagrammatically in Figs. 1 and 6) 70 which are secured to each end of the circular faces of the sector so that the chains or ropes pass in opposite directions there-around. The other ends of each of the two chains or ropes, or if a single chain or rope 75 be used for each sector, the center portion of the same, are or is secured to a drum or pulley *j* which may be rotated by hand through the medium of a tiller bar or its equivalent, or by power in any convenient 80 manner.

When two chains or ropes are used, they wind around the drum or pulley in opposite directions, that is to say while one chain or rope is being wound on the drum or pulley, 85 the other one is being paid out. Similarly if a single chain is attached to the drum, one end is drawn in and the other paid out. There are two drums or pulleys *j*, *k* or double drum surfaces for each sector. 90

The two chains or ropes before referred to for each rudder stock sector *e*, *f* pass around guide pulleys *m*, *n*, upon the opposite ends of slides *o*, *p*. The latter are traversed through equal distances in opposite directions by a right and left hand screwed spindle *q* which may be rotated by hand or by power in any convenient manner and which passes through nut-like parts *r*, *s*, one upon each slide. 95

With the arrangement before described, when the drums *j*, *k* to which the chains or ropes *i* of both sectors *e*, *f* are attached are rotated, the sectors are moved simultaneously in the same circular direction, the chain or rope attached to one end of a sector pulling for one direction of movement, the chain or rope attached to the other end of the sector pulling for the opposite direction of movement. When, however, the right and left hand screwed spindle *q* is rotated, it transverses the slides *o*, *p* carrying the guide pulleys, *m*, *n* in opposite directions, resulting in the sectors *e*, *f* being rotated through equal angles in opposite directions. The drums *j*, *k* may be rotated simultaneously with or after the movement of the screwed spindle *q* is completed, in order to effect steering of the boat while it is moving astern.

By the arrangement of the guide pulleys *m* and *n*, it will be seen that the movement given to each sector is twice that given to its slide, so that a relatively narrow operating gear only is required to give the angular movements necessary to the rudders to control the boat in its direction of travel.

The arrangement of the slides *o*, *p* with guide pulleys *m*, *n*, provides a rapid means for moving the sectors *e*, *f* in opposite directions for boat steering or speed variation purposes.

Instead of operating the slides *o*, *p* by a right and left hand screwed spindle, we may operate them by a pinion *u* (see Figs. 8 and 9) engaging two racks *v*, *w* one upon each side.

In the arrangement shown in Figs. 10, 11 and 12, the pulleys *m*, *n* which serve to deflect the chains or the like *i* so as to move the sectors in opposite angular directions, are operated by the links *x* from the lever *y* which is itself actuated by the hand lever *z*. Figs. 11 and 12 show the arrangement of the two chains or the like leading from the left hand ends of the sectors. At 4, 4 there are two superposed pulleys while the pulleys 5 are all single pulleys. A similar disposition of parts is provided for the chains or the like from the right hand ends of the two sectors. In this example, superposed pulleys *m*, *n* are mounted upon each slide, instead of two single pulleys at opposite ends of the slides as in the previous examples.

I may vary the details of my improved gear to suit any particular services or requirements.

Having now described my invention, what I claim as new and desire to secure by Letters Patent is:—

1. In boat steering and reversing gear, two coöperating rudders with rudder stocks, a part upon each rudder stock, rotatable means, two flexible connections between the

rotatable means and each part upon a rudder stock, and means deflecting simultaneously each pair of flexible connections, as set forth.

2. In boat steering and reversing gear, two coöperating rudders with rudder stocks, a sector upon each rudder stock, a rotatable element, flexible connections extending between the rotatable element and the two ends of each sector, and means deflecting simultaneously each pair of flexible connections, as set forth.

3. In boat steering and reversing gear, in combination, two coöperating rudders, concentric rudder stocks for the said rudders, a sector upon each rudder stock, a rotatable element, flexible connections between the rotatable element and the opposite ends of each sector, and means deflecting simultaneously each pair of flexible connections, as set forth.

4. In boat steering and reversing gear, in combination, two coöperating rudders with rudder stocks, a part upon each rudder stock, rotatable pulleys, two flexible connections between said pulleys and each part upon a rudder stock, and two pulleys deflecting simultaneously each pair of flexible connections, as set forth.

5. In boat steering and reversing gear, in combination, two coöperating rudders, concentric rudder stocks for the said rudders, a sector upon each rudder stock, rotatable pulleys, two flexible connections between said pulleys and the opposite ends of each sector, and two pulleys deflecting simultaneously each pair of flexible connections, as set forth.

6. In boat steering and reversing gear, in combination, two coöperating rudders with rudder stocks, a part upon each rudder stock, rotatable means, two flexible connections between the rotatable means and each part upon a rudder stock, two slides, two pulleys upon each slide, means traversing the slides simultaneously in opposite directions, the two flexible connections of each part upon a rudder stock passing around and being deflected by the two pulleys upon a slide, as set forth.

7. In boat steering and reversing gear, in combination, two coöperating rudders, concentric rudder stocks for the said rudders, a sector upon each rudder stock, a rotatable part, flexible connections between the rotatable part and the opposite ends of each sector, two slides, two pulleys upon each slide, means traversing the slides simultaneously in opposite directions, the two flexible connections from each sector passing around and being deflected by the two pulleys upon a slide, as set forth.

8. In boat steering and reversing gear, in combination, two coöperating rudders, concentric rudder stocks for the said rudders,

a sector upon each rudder stock, a rotatable part, flexible connections between said rotatable part and the opposite ends of each sector, two slides, nut-like parts upon each 5 slide, a right and left hand screwed spindle passing through said nuts to traverse the slides simultaneously in opposite directions,

the two flexible connections from each sector passing around and being deflected by the two pulleys upon a slide, as set forth. 10

In testimony whereof I have signed my name to this specification.

JOHN GEORGE AULSEBROOK KITCHEN.
